LIGHTER CONSTRUCTION

Walter J. Burchett, East Orange, N. J., assignor to Art Metal Works, Inc., Newark, N. J., a corporation of New Jersey

Application August 21, 1940, Serial No. 353,477

3 Claims. (Cl. 67—7.1)

The invention relates to lighters of the pyrophoric type and aims primarily to provide a lighter construction wherein exposed operating parts are reduced to a minimum, and such parts nevertheless readily accessible for adjustment and replacement, the construction as a whole being simple and compact, and in other respects advantageous for use in lighters combined with pencils, pens and the like. Further objects and advantages of the invention will be in part obvious and in part specifically referred to in the description hereinafter contained which, taken in conjunction with the accompanying drawing, discloses a preferred embodiment of the invention; such embodiment, however, should be considered only as illustrative from the standpoint of the invention in its broader aspects. In the drawing—

Fig. 1 is a central vertical section showing detached a lighter mechanism constructed to operate in accordance with the invention.

Fig. 2 is a plan view of the mechanism shown in Fig. 1.

Fig. 3 is a central vertical section showing a pencil construction with which the lighter mechanism of Fig. 1 is adapted to be combined.

Fig. 4 is a plan view of the construction shown in Fig. 3.

Figs. 5 and 6 are sections taken respectively on the line 5—5 of Fig. 2 and the line 6—6 of Fig. 1.

Fig. 7 is a side elevation showing the parts of Figs. 1 and 3 in assembled relation.

Referring more particularly to Figs. 1 and 3, the invention as illustrated is applied to a lighter mechanism combined with a pencil 1 having a stud 2 which screws into the bottom of a cylindrical barrel 3 which provides a fuel receptacle 4, access to which may be had by unscrewing stud 2, for purposes of supplying fuel or absorbent material. A wick tube 5 projects upwardly through the top wall 6 of chamber 4 and is provided with a snuffer seat 7 at its upper end.

The operating parts of the lighter mechanism are carried by a supporting member 8 which fits detachably into position on the upper portion of barrel 3. As shown the supporting member 8 is in the form of a hollow shell which slides telescopically over a reduced upper end portion 3a on barrel 3, until the support 8 seats against an annular shoulder 3b on the barrel.

The invention is shown as applied to a lighter mechanism having a snuffer member 9 pivoted about a spindle 10 which is supported in ears 11 extending upwardly from the top of supporting

member 8. As shown, these ears are a part of and extend upwardly from a bracket member 12 which is of U-shape cross section at its intermediate portion, as shown in Fig. 6. This bracket member 12 fits into a notch 13 (Fig. 6) in the side wall of supporting member 8, seating against a ledge 14 at the bottom of such notch, and is fixedly secured to member 8. As shown more particularly in Figs. 2 and 5, wings 12b may be provided, extending out laterally from the body of bracket 12 to the adjacent enclosing walls of supporting member 8, to brace the construction and provide a partial top wall for supporting member 8, which top wall however does not overlie the part of support 8 through which the wick tube 5 projects.

A sparking wheel 15 is journaled on shaft 16 and as shown gear members 16 (Fig. 5) on opposite sides of the snuffer 9, serve to rotate the snuffer and sparking wheel in a manner which need not be described in detail since suitable mechanisms for this purpose are well known in the art. A flint tube 17, having an adjusting screw 18 at its lower end, is shown as positioning the flint 19 (Fig. 5) underneath sparking wheel 15, this flint tube 17 being shown as supported by ears 20 (Fig. 5) extending inwardly from supporting member 8.

The side push operation above referred to is obtained by levers 21 pivoted at their lower ends about a shaft 22 mounted in downwardly extending ears 12a (12), the levers 21 thus being housed within the interior of supporting member 8, and being provided at their upper ends with gear teeth 23 which engage with the gears 16 above referred to. A finger-piece 24, however, is connected to the levers 21 and projects outwardly between ears 11 so as to be exposed at one side of supporting member 8.

Thus when the parts are assembled into the relation shown in Fig. 7, by sliding the supporting member 8 over extension 3a, the snuffer seat 7 normally comes into seating position with respect to snuffer 9, the wick tube 5 projecting upwardly through the space inside of the hollow support 8, and the flint tube 17 projecting downwardly into the space within the extension 3a. A notch 3c in extension 3a receives the bracket 12, and insures that the wick tube 5 will be properly aligned with snuffer 9 when the parts are assembled.

In operation the user grasps the barrel 3 within his hand, and pushes the finger piece 24 to the left (as shown in Fig. 1) with thumb or finger, thus swinging the snuffer 9 upwardly to

expose the wick and projecting sparks on to the wick from wheel 15. A spring 25 normally urges lever 21 and finger-piece 24 to the right (as shown in Fig. 1) thus normally holding snuffer 9 sealed against seat 7, and restoring the snuffer 9 to closed position whenever manual pressure on finger-piece 24 is released, after a light has been obtained.

Thus portion of the side push type is obtained by means of actuating levers which, with the exception of the finger-piece 24 exposed at the side of supporting member 8, are housed within such supporting member. When it is desired to adjust pressure on the flint 19, the supporting member 8 carrying the movable operating parts of the lighter mechanism is slid off the end of barrel 3, thus affording access to the screw 18, without disturbing the fuel receptacle. When fuel is to be supplied to chamber 4, it is merely necessary to unscrew the stud 2, and the flint tube 17, being located entirely above chamber 4, does not interfere with access to the latter. Adjustment or replacement of the wick in tube 5 may also be readily made by disassembling the parts 3 and 8 as above described, the entire construction presenting a minimum of protruding operating parts, and such parts being nevertheless readily accessible.

While the invention has been disclosed as carried out by a lighter construction of the specific form above described, it should be understood that changes may be made therein without departing from the invention in its broader aspects, within the scope of the appended claims.

I claim:

1. A lighter construction of the class described including a hollow casing containing a fuel compartment, a hollow supporting member of substantially the same cross sectional area as said fuel compartment, said hollow supporting member detachably fitting the upper portion of said casing and extending upwardly above said fuel compartment, a wick tube carried by said casing and projecting upwardly from said fuel compartment through said hollow supporting member to the upper portion thereof, a snuffer movably mounted upon the upper portion of said supporting member in position to engage the upper end of said wick tube, a sparkling wheel also carried by the upper portion of said supporting member and an operating member of the side-push type for said snuffer and sparkling wheel, said operating member being carried by said supporting member and mounted in the space above said fuel compartment, and being largely housed within said supporting member but having a finger-engaging portion which is exposed at one side of said supporting member at the upper portion thereof, said snuffer, sparkling wheel and operating member being constructed and arranged to cause inward pressure upon said finger en-

gaging portion to remove said snuffer from the wick tube and rotate said sparkling wheel, and a flint tube located beneath said sparkling wheel, said flint tube being also carried by and detachable with said supporting member.

2. A lighter construction of the class described including a hollow casing containing a fuel compartment, a hollow supporting member of substantially the same cross sectional area as said fuel compartment, said hollow supporting member detachably fitting the upper portion of said casing and extending upwardly above said fuel compartment, a wick tube carried by said casing and projecting upwardly from said fuel compartment through said hollow supporting member to the upper portion thereof, a snuffer movably mounted upon the upper portion of said supporting member in position to engage the upper end of said wick tube, a sparkling wheel also carried by the upper portion of said supporting member, an operating lever for said snuffer and sparkling wheel, said lever being carried by said hollow supporting member and pivoted near its lower end in the space above said fuel compartment, said lever having a finger engaging portion which is exposed at one side of said supporting member at the upper portion thereof.

3. A lighter construction of the class described including a hollow casing containing a fuel compartment, a hollow supporting member of substantially the same cross sectional area as said fuel compartment, said hollow supporting member detachably fitting the upper portion of said casing and extending upwardly above said fuel compartment, a wick tube carried by said casing and projecting upwardly from said fuel compartment through said hollow supporting member to the upper portion thereof, a snuffer movably mounted upon the upper portion of said supporting member in position to engage the upper end of said wick tube, a sparkling wheel also carried by the upper portion of said supporting member and an operating member of the side-push type for said snuffer and sparkling wheel, said operating member being carried by said supporting member and mounted in the space above said fuel compartment, and being largely housed within said supporting member but having a finger-engaging portion which is exposed at one side of said supporting member at the upper portion thereof, said snuffer, sparkling wheel and operating member being constructed and arranged to cause inward pressure upon said finger engaging portion to remove said snuffer from the wick tube and rotate said sparkling wheel, said hollow supporting member also having carried thereby and located therewithin a downwardly extending flint tube located in the space above said fuel compartment.
